UNITED STATES PATENT OFFICE

165,716

SANDAL

George S. Laham, Wichita, Kans.

Application March 17, 1951, Serial No. 14,528

Term of patent 14 years

(Cl. D7—7)

To all whom it may concern:

Be it known that I, George S. Laham, a citizen of the United States and a resident of the city of Wichita, in the county of Sedgwick and State of Kansas, have invented a new, original, and ornamental Design for a Sandal, of which the following is a specification, reference being had to the accompanying drawing, forming a part thereof.

On the drawing:

Figure 1 is a front perspective view of the sandal, showing my new design; and

Figure 2 is a rear perspective view thereof.

The essential features of my design for a sandal reside in the appearance of the toe portion, which is slit at spaced intervals and then a drawstring is passed through apertures in each seg-

ment in a manner so as to make the overlapping of said segments to conceal, or partially conceal the drawstring, all as illustrated on the drawing.

I claim:

The ornamental design for a sandal, as shown and described.

GEO. S. LAHAM.
